ELECTRIC SIGNAL SYSTEM

Filed Sept. 22, 1927

UNITED STATES PATENT OFFICE

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTRIC SIGNAL SYSTEM

Application filed September 22, 1927. Serial No. 221,151.

This invention relates to signal systems, and more particularly to an electric signal adapted for use on railway trains.

An object of my invention is to provide a train signal system by the use of which the trainman may signal the engineman from any car of a train and by which the engineman may cause his reply signal to be transmitted to the car station from which the trainman's signal originated and further, by which the engineman may cause a signal originated by him to be transmitted to every car station on the train.

Another object of the invention is to provide a train signal system in which each car of a train is provided with a signal device operable by direct current and a signal device operable by alternating current and in which the flow of current to one or the other of said devices is selectively controlled from the locomotive of the train.

These and other objects and advantages will appear in the following more detailed description of the invention.

In the accompanying drawing the single figure is a diagrammatic view of a train signal system embodying my invention.

According to my invention, the locomotive or controller car of a railway train may be provided with a source of alternating electric current, such as the ordinary generator 1, to which is connected a transformer 2 adapted to reduce the voltage of the current flowing from the generator, to that desired for the operation of the signal system. One end of the coil 3 of this transformer is connected to ground at 4 and the other end is connected to a contact 5 of the engineman's switch. The engineman's switch also has a contact 6 which is connected to ground at 7 and further, has a pivotally mounted arm 8 adapted to be normally held in contact with the contact 6, by a spring 9 and is adapted to be operated manually, against the resistance of the spring 9, into contact with the contact 5. This switch arm 8 is connected to one terminal of a signal indicating device which may comprise a motor 10 having a vibrator disc 11 mounted on and rotatable with the armature shaft of the motor, which disc is adapted to engage with

a diaphragm 12, associated with a horn 13, so that, upon the operation of the armature, the disc will be rotated causing the diaphragm to vibrate and produce a sound through the horn which will be audible to the engineman. The other terminal of the signal indicating device is connected to a train wire 14 which may be, in effect, continuous throughout the length of the train.

Each car of the train may be provided with a signal indicating device such as the buzzer 15 which is adapted to be operated by an alternating current only. One terminal of this buzzer is connected to the train wire 14 and the other terminal is connected to ground at 16.

Each car may be further provided with a signal indicating device 17, a trainman's switch device 18 and a source of current, such as the battery 19. The signal indicating device 17 may comprise coils 20 and 21, a core 22 and a pivotally mounted vibrator arm 23 adapted to normally engage a contact 24 which is connected, by a wire 25, to a terminal contact 26 of the trainman's switch device 18. One terminal of the coil 20 is connected to the train wire 14 and the other end is connected with the wire 25. One end of the coil 21 is connected to a terminal contact 27 of the trainman's switch device 18 and the other end is connected to the arm 23 which is normally held in contact with the contact 24 by a spring 28.

The trainman's switch device 18 comprises a casing containing a contact member 29 having an operating stem 30 adapted to be operated by a lever 31 having operating arms 32 and 33, each having an operating cord 34 connected therewith. Mounted on the casing, there are fulcrum pins 35 and 36, which are so disposed, that when the arm 32 is operated, the lever 31 turns about the pin 35 and when the arm 33 is operated the lever turns about the pin 36, in either case the stem 30 is operated.

The contact member 29 is provided with contacts 37 and 38 and is normally maintained in the position shown in the drawing by the action of a spring 39 mounted in the casing. This member 29, when it is moved a

predetermined distance, engages a yielding stop member 40 which is subject to the pressure of a spring 41 mounted in the casing. In order to prevent rotative movement of the contact member 29, a guide bushing having screw-threaded engagement with the casing of the switch device 18, is provided with a pin 42 which engages in a grooved formed in the contact member.

10 The contact 37 of the trainman's switch device 18, controls circuit wires connected to the terminal contact 27, and to a terminal contact 43 connected to ground at 44. The contact 38 controls circuit wires connected 15 to the terminal contact 26, and to a terminal contact 45 connected to the positive terminal of the battery 19, the negative terminal of which battery is connected to ground at 46.

Assuming the several parts of my invention to be in their normal positions, as shown 20 in the drawing, and the trainman desires to signal the engineman, the trainman pulls the operating cord 34 until the contact member 29 engages the stop member 40, in which position, the contact 38 connects the terminal contacts 26 and 45, which permits current to 25 flow from ground 46, through the battery 19, wire 25 and coil 20 of the signal device 17 to the train wire 14 and therethrough to the motor 10 and from thence, through the arm 8 of the engineman's switch to ground 7 and the current flowing through this circuit will cause the motor to operate so that the diaphragm 12 of the engineman's signal device 30 will be vibrated and produce sounds audible to the engineman. If the trainman holds the contact member 29 in this position, a substantially continuous sound is produced, but the trainman by operating his switch up and 35 down to open and close the circuit, may cause the engineman's signal device to operate intermittently and thereby convey to the engineman any predetermined signal.

It will here be noted that when current 40 flows through the coil 20 of the trainman's signal device 17, the armature 22 is magnetized, which causes the arm 23 to be attracted to it, thus moving the arm 23 out of contact with the contact 24.

50 Should the trainman desire to receive the engineman's reply signal at the car station from which he initiated his signal, he causes the contact member 29 to be moved to its final depressed position, in which, the contact 55 37 connects the terminal contacts 43 and 27 thus connecting the arm 23 and coil 21 of the trainman's signal device 17 to ground 44. In this position of the contact member 29, the contact 38 still connects the contacts 26 and 45 and the circuit for operating the engineman's signal is maintained closed as hereinbefore described. To reply to the trainman's signal, the engineman moves the arm 8 of his switch device out of contact 60 65 with the contact 6 which opens the circuit

described, which permits the core 22 to become demagnetized, thus permitting the spring 28 to move the arm 23 into contact with the contact 24, and when in such contact, current will flow from the contact 24, 70 through the arm 23, coil 21 and contact 37 to ground 44. Current thus flowing through the coil 21 causes the core 22 to become magnetized and the arm 23 is attracted to it, against the influence of the spring 28, thus 75 opening the circuit again, which permits the arm 23 to be moved again, by the action of the spring 28, into contact with the contact 24, and these operations continue so long as the arm 8 is maintained out of contact with the contact 6, and the signal device 17 will 80 produce a substantially continuous sound. By opening and closing the circuit by the use of the engineman's switch, the engineman may cause the intermittent operation of the trainman's signal device 17, and thereby 85 transmit to the trainman any predetermined signal.

Should the engineman desire to initiate a signal to be sounded at every car station 90 throughout the length of the train, he moves the arm 8 of his switch so that it contacts with the contact 5, which permits alternating current to flow from the generator 1 and transformer 2, through the engineman's 95 switch device, and engineman's signal indicating device to the train wire and from thence through each of the signal devices 15 to ground 16, thus operating all of the signal devices 15. By opening and closing this circuit through the operation of the arm 8, the engineman may cause any desired signal to 100 be transmitted to the trainman. It will here be understood that the signal devices 15 are operable by alternating current only, so that when the trainman is signalling the engineman or when the engineman is replying to the signal initiated by the trainman, the direct current, from the battery, flowing through the train wire 14, will not cause the signal devices 15 to operate.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. In a train signal system, the combination 110 with a single train wire, of an electrically controlled signal indicating device on the head vehicle of a train and connected to said train wire, an electrically controlled signal indicating device on each of the other vehicles 115 of the train and connected to said train wire and each comprising an electro-magnet, a switch device on the head vehicle normally connecting said train wire to ground, a source 120 of current on each of said other vehicles per 125

manently connected to ground, a switch on each of said other vehicles operative to one position to connect the local source of current in circuit with said train wire to cause

the head vehicle and operative when the switch is operated to disconnect the train wire from ground when the local switch device is in its second mentioned position.

5 the signal device on the head vehicle to operate, and operative to another position to maintain said local source of current connected to said train wire and to connect the local signal device on the vehicle to ground, 70
10 the switch device on the head vehicle being operative to disconnect said train wire from ground, and means included in each electromagnet operative to intermittently connect and disconnect the local source of current to 75
15 and from ground and cause a signal to sound when said train wire is disconnected from ground and the local switch device is in its second mentioned position.

2. In a train signal system, the combination

20 with a single train wire, of an electrically controlled signal indicating device on the head vehicle of a train and connected to the train wire, an electrically controlled signal indicating device on each of the other vehicles of the 25 train and each connected to said train wire, a source of current on each of said other vehicles permanently connected to ground, a switch device on the head vehicle of the train normally connecting said train wire to 30 ground, a switch device on each of said other vehicles for closing a circuit through the local source of current and the signal device on the head vehicle, and having a position for connecting the local signal device to ground and 35 connecting said local source of current to said train wire, and to the local signal device, the switch device on the head vehicle being operative to a position to disconnect said train wire from ground, and means included in the local 40 signal device operative to intermittently connect and disconnect the local source of current to and from ground and cause a signal to sound when said train wire is disconnected from ground and the local switch device is in its second 45 mentioned position.

3. In a train signal system, the combination

50 with a single train wire, of an electrically controlled signal indicating device on the head vehicle of a train and connected to said train wire, an electrically controlled signal indicating device on each of the other vehicles of the train, a source of current on each of said other vehicles permanently connected to ground, a switch on the head vehicle normally connecting said train wire to ground, a switch device on each of said other vehicles operative to one 55 position to connect the local source of current in circuit with the signal device on the head vehicle, and operative to another position to connect the local signal device to ground and to connect said local source of current to said train wire, and means included in the signal device of each of said other vehicles for rendering it inoperative when the train wire is 60 connected to ground through the switch on

the head vehicle and operative when the switch is operated to disconnect the train wire from ground when the local switch device is in its second mentioned position.

4. In a train signal system, the combination with a single train wire normally connected to ground at the head of the train, of an electrically controlled signal indicating device on the head vehicle of a train connected to said train wire and operative by direct current, a source of direct current permanently connected to ground on each of the other vehicles of the train, a switch device on each of said other vehicles operative to close the circuit through the local source of current and the signal device on the head vehicle to cause the signal device to operate, an electrically controlled signal indicating device on each of said other vehicles connected to said train wire and to ground and operative by alternating current, another electrically controlled signal indicating device on each of said other vehicles connected to said train wire and operative by direct current, said switch devices each having another position to connect the local source of direct current to said train wire and to connect the direct current operated signal device on each of said other vehicles to ground, means operative to one position from the head vehicle for disconnecting said train wire from ground and operative to another position for connecting said source of alternating current in circuit with the alternating current operated signal devices, and means included in each of the direct current operated signal devices operative to control the flow of current through the local source of direct current and the local signal device when the local switch device is in its second mentioned position.

5. In a train signal system, the combination with a single train wire normally connected to ground at the head of the train, of an electrically controlled signal indicating device on the head vehicle of a train, and connected in said train wire, an electrically controlled signal indicating device on each of the other vehicles of the train, the last mentioned signal devices comprising an electromagnet having plurality of coils and a vibrator, one of said coils being connected at one end to said train wire and at the other end to a circuit wire, a source of current connected to ground on each of the other vehicles, a switch device on each of said other vehicles having means operative to a position for cutting the local source of current in circuit with said circuit wire, connected coil and the signal device on the head vehicle, and another position for connecting said local source of current to said train wire and to connect the other coil of said local signal device to ground, the current flowing to said train wire through the circuit

wire and first mentioned coil causing said vibrator of the local signal device to operate to prevent the flow of current through the second mentioned coil to ground, and means operative from the head vehicle for disconnecting said train wire from ground to permit the vibrator to operate to intermittently make and break the circuit through the second mentioned coil.

6. In a train signal system, the combination with a train wire normally connected to ground at the head of the train, of a source of electric current on each vehicle of the train having one terminal permanently connected to ground, an electrically controlled signal indicating device on each vehicle of a train, each signal indicating device having one of its terminals permanently connected to said train wire and another of its terminals normally disconnected from ground, means on each vehicle operative to a position to connect the local source of current in circuit with said signal device and to connect the last mentioned terminal of the local signal device to ground, means included in each signal device operative by current flowing from said source to ground through said train wire for rendering each signal device inoperative to effect a signal, and operative by current flowing from said source when the first mentioned means is in position to connect the signal device in circuit with said source and ground to effect a signal upon the disconnection of said train wire from ground, and a switch device at the head of the train operative to connect and disconnect the train wire to and from the ground.

7. In a train signal system, the combination with a train wire, of a switch device on the head vehicle of a train normally connecting said train wire to ground and operative to a position to disconnect said train wire from ground, a source of current on each of the other vehicles of said train and each having one terminal permanently connected to ground, an electrically controlled signal indicating device on each of said other vehicles of the train and each having one terminal connected to said train wire and another terminal normally disconnected from ground, means on each of the last mentioned vehicles operative to a position to connect the local source of current in circuit with a local signal device and to connect the last mentioned terminal of the local signal device to ground, and means included in said local signal device for rendering the signal device inoperative to effect a signal when the current from said source is flowing to ground through said train wire and the switch on the head vehicle, and additional means for rendering said local signal device operative by current flowing from said source to

ground when the switch device on the head vehicle is operated to disconnect said train wire from ground.

In testimony whereof I have hereunto set my hand.
